REFLECTIVE ROADWAY MARKER

Howard A. Schaefer, Lancaster, Ohio, assignor to Anchor Hocking Corporation, Lancaster, Ohio

Filed Apr. 25, 1973, Ser. No. 354,178

Term of patent 14 years

Int. Cl. D29—02

U.S. Cl. D72—1 J

Fig. 1.

Fig. 2.

Fig. 4.

Fig. 3.

FIG. 1 is a top plan view of a reflective roadway marker showing my new design;

FIGS. 2-3 are front elevation and bottom plan views, respectively, of the reflective roadway marker shown in FIG. 1; and

FIG. 4 is a side elevation view partly in cross-section of the reflective roadway marker shown in FIGS. 1-3.

I claim:

The ornamental design for a reflective roadway marker, substantially as shown and described.
